OVEN PLATE

Harry Kaplan, Brooklyn, N. Y.

Application May 10, 1944, Serial No. 534,893

1 Claim. (Cl. 126—22)

This invention relates to an oven plate, particularly although not exclusively of the type adapted for placement upon the floor of a baking and roasting oven having the source of heat disposed below the oven floor.

Conventional ovens, especially those that are gas-fired, are generally so constructed that the flame is concentrated upon certain localized areas of the oven floor, thereby causing a rapid deterioration of such floor where the heat is most intense. Furthermore, due to the fact that the oven floor is generally made of conducting material, the hottest regions thereof are those directly above the flame, the heat being transmitted through these regions at a more rapid rate than through other parts of the floor relatively remote from the flame. There is thus an uneven distribution of heat, resulting in scorched foods which are in close proximity to the areas of the oven floor where the heat transmission is most rapid, and underheated conditions for foods more remotely situated. It is primarily within the contemplation of my invention to overcome these shortcomings by more evenly distributing the heat along the oven floor, and by effectuating a ventilation of said floor and an equal distribution of heat into the oven chamber.

In accordance with the preferred form of my invention, the above-mentioned objectives are accomplished by means of an oven plate provided with a horizontal wall of heat-storing and diffusing material, such as asbestos, together with an arrangement which will effectively permit a circulation of heated air to take place substantially along the entire extent of the heat-storing sheet, and the regions of the oven floor and oven chamber adjacent the said sheet. And in this aspect of my invention it is an important object to provide a casing associated with the said heat-storing wall which will permit an effective circulation of heated air both below and above the said wall.

Many ovens of the above-referred-to class have the opposite lateral walls of their heating chamber provided with inwardly extending supports or ridges for supporting, in parallel relation to the floor of the oven, one or more grids or removable floors. It is another object of my invention to enable an oven plate of the class described to be operatively placed upon the floor of the oven and capable of clearing the aforesaid supports or ridges disposed adjacent the floor or the oven.

It is another object of my invention to provide a readily-fabricated casing with which the heat-storing wall can be quickly and easily assembled.

Other objects, features and advantages will appear from the drawing and description herein-after given.

Referring to the drawing,

Figure 1 is a perspective view of a preferred form of the oven plate of my invention shown operatively in position upon the floor and between the walls of an oven, the drawing showing only fragmentary portions of said oven floor and walls.

Figure 2 is a rear view of Figure 1, looking in the direction of the arrows, and

Figure 3 is a section of Figure 2 taken along line 3—3.

15 In the particular form of my invention illustrated in the drawing, the oven plate 10 is shown resting upon the oven floor 11 between the side walls 12 and 13 of the oven. The oven plate proper consists of a casing 14 having an upper wall 15, a rear wall 16, a front wall 17 and side walls containing the channel-shaped retaining portions 18 and 19. Within said retaining portions 18 and 19, and slidably supported thereby, is a heat-storing and heat-diffusing wall 20. In 20 the preferred form of my invention this wall is a sheet of insulating material like asbestos, the sheet being of sufficient stiffness to be self-supporting. Although said wall is hereinafter referred to as a heat-storing wall, it is intended, within the scope of this invention, that it may be also considered as a wall of heat-diffusing properties, as is characteristic of asbestos.

Disposed directly above the heat-storing sheet 20 is the air-space compartment 21, this being formed by the upper wall 15 of the casing, the front and rear end walls 17 and 16 thereof, respectively, and the side walls 21 and 22. It is preferred that the front wall 17 extend downwardly from the upper wall 15 approximately to the level of, but not below, the upper surface 23 of the heat-storing sheet 20, so as to permit said sheet to be slidably inserted within the channel-like recesses of the retaining members 18 and 19. It is also preferred that the rear wall 16 extend 25 downwardly from the upper wall 15 to a point below the level of the upper surface 23 of the said heat-storing sheet 20, so as to serve as an abutment or stop for holding said sheet 20 against rearward movement therebeyond.

The base of the casing 14 consists of two inwardly extending legs 24 and 25 of the retaining members 18 and 19 respectively, said legs being adapted to rest upon the oven floor 11. It is thus apparent that with such an arrangement, 30 an air space 26 is provided between the oven floor

11 and the bottom surface of the heat-storing sheet 20.

It will also be observed that the air-space compartment 21 communicates with the atmosphere through the aperture 27 at the rear of the top of the casing and the apertures 28 at the front of the casing. It is understood, however, that other forms and positions of the apertures equivalent to 27 and 28 may be employed in association with the casing 14, with equal force and effect.

In the operation of this device, the source of heat, not shown in the drawing, is applied to the under-surface of the oven floor 11, in conventional manner. The heat transmitted through said wall causes the air in space 26 to be heated, and this heated air will cause a heating of the heat-storing sheet 12. Due to the nature of the material of sheet 20, it will absorb a considerable portion of the heat transmitted to it before giving off its heat to the region thereabove. It has been found that said sheet 20 will generally become heated substantially uniformly throughout the extent thereof; and thereafter the heat from said heat-storing sheet will travel upwardly into the space 21, to heat the upper wall 15 thereof uniformly throughout its entire extent. The uniform heating of the said upper wall 15 will consequently cause a uniform distribution of heat in the region thereabove, thereby effectuating an even distribution of heat throughout the food or other products being heated within the oven in the region directly above the oven plate.

The openings 27 and 28 serve to aid in the circulation of the heated air within compartment 21. When the sheet 20 is of porous material, these apertures, through their draft effect, induce the passage of heated air, gases or vapors upwardly through sheet 20 into the compartment 21 out through the apertures. However, circulation will take place even if the material of sheet 20 is non-porous, inasmuch as air will pass through the front and rear openings 29 and 30 of said space 26, and through said openings 27 and 28 in upper wall 15, due to the difference in temperature between the atmosphere and the air within the said space 26 and compartment 21.

This continuous circulation of air in space 26 will obviously produce a ventilating and cooling effect upon the oven floor 11, and also an equal distribution of heat within the upper wall 15 of the casing. Such effects are also brought about, and enhanced, by virtue of the fact that the heat-storing and diffusing properties of sheet 20 enable it to absorb heat uniformly throughout its extent, thereby uniformly drawing heat from all portions of floor 11 and uniformly transferring its heat to the air within compartment 21.

In the form of oven illustrated in the drawing, the side walls 12 and 13 thereof contain angle-bars 31 and 32, these serving as supports for wire grids or removable supports that are to be disposed above the floor of the oven. I have made provision for the contingency where said angle-bars 31 or similar supports are positioned in proximate relation to floor 11 of the oven, by providing the oven plate with recessed portions 33 and 34 for the purpose of clearing said supports 31.

In the form of my invention illustrated, the entire casing 14 is formed of sheet-metal construction, although it is understood that other methods of construction and other materials may be employed. In the sheet-metal construction illustrated, the base of the oven plate is readily bent into shape to provide the channel-like retaining members 18 and 19, the upper walls 35 and 36 of said retaining members constituting the recessed walls provided to clear the angle bars 31. The front and rear portions 17 and 18 of the sheet-metal construction are bent downwardly to form front and rear flaps. The inwardly extending legs 24 and 25 serve not only as part of the retaining members for the heat-storing sheet 20, but also as spacing means for keeping said sheet spaced from the floor 11. This construction is particularly feasible where the sheet 11 is made of relatively stiff board capable of sustaining itself throughout its extent. It is thus apparent that the entire construction can be readily fabricated and assembled to produce a device capable of effecting the objectives hereinabove stated.

It is understood that the embodiment above described and shown in the drawing is merely illustrative of my invention, and that numerous changes and modifications may be made therein within the scope of the appended claim without departing from the spirit of this invention.

I claim:

An oven plate adapted for placement upon an oven floor, comprising a sheet-metal casing containing a top wall, two opposite downwardly extending side sections the lower portions of which are channel-shaped with inwardly extending legs and the upper portions of which are recessed inwardly, two opposite end walls extending downwardly from the top wall, one of said end walls extending down substantially to the top of said channel-shaped portions and the other of said end walls extending down therebelow, the said top wall containing apertured means; and a wall of heat-storing material disposed within and supported by said channel-shaped portions.

HARRY KAPLAN.
